SPARK PLUG

Hector Rabexana, Flint, Mich., assignor to General Motors Corporation, Detroit, Mich., a corporation of Delaware

Application June 1, 1937, Serial No. 145,662

5 Claims. (CL. 123—169)

My invention relates to spark plugs and the object thereof is to provide an improved single piece plug, wherein the parts which comprise the same are permanently secured together and provide a unitary structure, which is simpler in construction than has heretofore been the case in plugs of that type; and which, while gas tight and effective for the service required of it, may be made at less cost than heretofore. A further feature of advantage inherent in my invention consists in that the insulating member of the plug remains cooler than has usually been the case in single piece spark plugs, this being due to the fact that the external atmosphere has free access to a considerable part of the peripheral surface thereof.

The drawings accompanying and forming a part of this specification illustrate various embodiments of my invention, and the features wherein the same consists are particularly pointed out and claimed in the concluding claims.

In the drawings:

Figure 1 is a view showing the metal parts in section, and the insulating member of my improved spark plug in side elevation.

Figure 2 is a view showing the entire plug in side elevation, so that a better understanding may be had as to how the external atmosphere has direct access to the central part of the insulating member.

Figure 3 is a view showing a section upon a transverse plane indicated by the line 3—3, Figure 1.

Figure 4 is a view showing a half section and half elevation of a modified form of my invention.

Figure 5 is a view showing a section upon a transverse plane indicated by the line 5—5, Figure 4.

Figure 6 is a view showing a half section and half elevation of a spark plug similar to the one shown in Figures 1 and 2, but wherein the annular holding member thereof is modified.

Figures 7 and 8 are sectional and fragmentary views showing another form of my invention.

Figure 9 is a view showing the metal parts in section and the insulating member in side elevation, of a modified form of my invention.

Figure 10 is a view showing a section upon a transverse plane indicated by the line 10—10, Figure 9.

Referring now to the drawings, the numeral 11 designates an annular base member the lower or inner end of which is threaded to screw into an opening in the cylinder of an internal combustion

engine, and the upper or outer end of which has a flange 12; and the numeral 13 designates the insulating member of the plug which is commonly made of porcelain or similar ceramic material, and the lower end of which extends into the 5 threaded part of the base as shown. The insulated member has a passage extending longitudinally through it for the central electrode, the lower end 14 of which is disposed adjacent the grounded electrode 15 as is usual in spark 10 plugs. The base member is substantially the same in each of the forms of my invention illustrated, as is also the insulating member 13, although the enlarged central part thereof is somewhat shorter in Figures 4, 6, 7 and 9 than in 15 Figures 1 and 2.

The central part of the insulating member is enlarged as at 16, as is usual in spark plugs, and a lower annular shoulder thereof rests upon the flange 12 whereby the insulating member is supported from the base. As is also usual in spark plugs the base or flange is shown as provided with a narrow annular ridge 17 for securing a more perfect gas tight joint as the parts of the plug are assembled under pressure as will hereinafter 20 appear.

The numeral 18, Figures 1 and 2, designates an annular substantially cylindrical holding member which surrounds the upper part of the insulating member, and has an inwardly extending 30 flange 19 at its upper end. The insulating member has an upper annular shoulder 20; and 21 is an annular metallic member C-shaped in cross section and which is made of resilient material, this member being interposed between the flange 35 19 and the shoulder 20. In assembling the parts pressure is applied to the upper end of the holding member 18 (the base member 11 being supported upon the anvil of a suitable press) whereupon the resilient washer or gasket member 21 is 40 distorted by compression and acts as a strong and stiff spring to force the insulating member against the base throughout the life of the plug. The holding member is shown as having a series of depending lugs 22 which contact with the 45 periphery of the annular flange 12, and the lower ends of these lugs are welded, brazed or otherwise fastened to said flange while pressure is maintained between the holding member and the base and the annular member 21 is held under 50 compression, whereby the parts of the plug are held in a permanently assembled condition with the member 21 under stress during the life of the plug.

Figures 4 and 5 show a form of my invention 55

wherein the annular holding member and the resilient member or gasket which acts to force the insulating member against the base are made integral with one another, as distinguished from 5 as separate elements as in Figures 1 and 2; said member being made for example from spring steel flat stock and having an inwardly curved part or ring 23 which is C-shaped in cross section which is pressed against the annular shoulder 20 of the 10 insulating member when the parts are assembled under pressure, as aforesaid, the annular holding member of which the C-shaped ring 23 is a part having also a series of depending lugs 24, the lower ends of which are secured, preferably by 15 welding or brazing, to the annular flange 12 before the pressure whereby the part 23 is compressed so as to set up stress therein is relieved, thus and as in the form of my invention first described holding the parts of the plug together and 20 providing a unitary spark plug.

It will be seen that in both the forms of my invention thus far described the lugs 22 and 24 are spaced quite widely apart so that the surrounding atmosphere has comparatively free access to 25 the insulating member of the plug, which results in that the insulating member is kept cooler than would be the case if the openings or recesses between the lugs were not present.

Figure 6, however, shows a form of my invention 30 wherein such openings are not present. In this form the cylindrical holding member 25 extends to the flange 12 and fits about the periphery thereof, and is fastened thereto while the parts of the plug are held together under compression, 35 the same as in all the forms of my invention herein described. The holding member 25 while it has no openings between depending lugs is commonly slitted up from the lower end thereof to insure better contact with the flange 12 during 40 welding of the parts together, as indicated by the reference numeral 26.

Figures 7 and 8 illustrate a form of my invention 45 wherein the annular holding member is in the form of an upper narrow flange 27 having depending lugs 28 integral therewith and the lower ends of which are welded or brazed to the flange 12 of the annular base 11; and wherein the annular resilient C-shaped member 29 approaches more nearly a torus than does the 50 equivalent member 21 in Figures 1, 6 and 9. This member 29 is held under compression in the finished plug between the flange 27 and the annular shoulder 30 of the insulating member the same as in the other forms of my invention herein described. 55

Figures 9 and 10 illustrate a form of my invention wherein the member 31 which holds the parts of the plug together and in permanently assembled relation is of conical rather than 60 cylindrical form, and wherein the lugs 32 have hook-like extremities which enter a groove 33 in the flange 12 as the parts are assembled. The part 31 has a flange 34 at its upper end which holds a C-shaped resilient member 35 made, for 65 example, of spring steel, between itself and an annular shoulder 36 upon the insulating member 13; and during the assembling of the parts the holding member 31 with its lugs 32 partially bent inward is pressed toward the base 11, thus 70 subjecting the C-shaped member 35 to compression and producing a permanent distortion thereof and stress therein and, while the parts are held under compression, the hook-shaped extremities of the lugs 32 are forced inward and 75 into the groove 33. Engagement between these

parts will in many cases form a satisfactory method of holding the parts together although the lower ends of the lugs may be brazed or welded in place in the groove, thus forming a 5 stronger and more secure connection between the annular holding member and the base of the plug.

Having thus described and explained my invention I claim and desire to secure by Letters 10 Patent:

1. In a spark plug, an annular base having an inner externally threaded part, and an annular flange at its outer end; an insulating member supported by said base and extending into said threaded part, and having an annular shoulder; an annular holding member surrounding said insulating member and having depending lugs which are fastened to said annular flange, to thereby hold said insulating member permanently 20 assembled with said base; an annular metallic and resilient member arranged between said holding member and said shoulder; a central electrode extending through a passage in said insulating member; and a grounded electrode at the inner extremity of said threaded portion. 25

2. In a spark plug, an annular base having an inner externally threaded part, and an annular flange at its outer end; an insulating member supported by said flange and extending into said threaded part, and having an annular shoulder 30 spaced apart from said flange; an annular holding member surrounding said insulating member and extending above said shoulder and having an inwardly extending flange at its upper end, and which holding member has depending lugs 35 which are welded to said annular flange to thereby hold said insulating member permanently assembled with said base; an annular metallic and resilient member arranged between the flange at the upper end of said holding member and 40 said shoulder; a central electrode extending through a passage in said insulating member; and a grounded electrode at the inner extremity of said threaded portion.

3. In a spark plug, an annular base having an 45 inner externally threaded part, and an annular flange at its outer end; an insulating member supported by said flange and extending into said threaded part, and having an annular shoulder spaced apart from said flange; an annular holding member cylindrical in form surrounding said insulating member and extending above said shoulder and having an inwardly extending flange at its upper end, and the lower end of 50 which holding member is fastened to the periphery of said annular flange to thereby hold said insulating member permanently assembled with said base; an annular metallic and resilient member C-shaped in cross-section arranged between the flange at the upper end of said holding member and said shoulder; a central electrode extending through a passage in said insulating member; and a grounded electrode at the inner 55 extremity of said threaded portion.

4. In a spark plug, an annular base having an 60 inner externally threaded part, and an annular flange at its outer end; an insulating member supported by said flange and extending into said threaded part, and having an annular shoulder spaced apart from said flange; an annular holding member cylindrical in form surrounding said insulating member and extending above said shoulder and having an inwardly extending flange at its upper end, and which holding member 65 has depending lugs the lower ends of which 70

75

- are welded to the periphery of said annular flange to thereby hold said insulating member permanently assembled with said base; an annular metallic and resilient member C-shaped in cross-section arranged between the flange at the upper end of said holding member and said shoulder; a central electrode extending through a passage in said insulating member; and a grounded electrode at the inner extremity of said 10 threaded portion.
5. In a spark plug, an annular base having an inner externally threaded part, and an annular flange at its outer end; an insulating member supported by said annular flange and extending 15 into said threaded part and having an annular shoulder; an annular holding member separate from said base surrounding said insulating member and having an inwardly curved upper end which is C-shaped in cross-section, and resilient, and which inwardly curved upper end overlies the shoulder aforesaid, the lower end of said holding member being welded to the periphery of said annular flange to thereby hold said insulating member permanently assembled with said base; a central electrode extending through a 10 passage in said insulating member; and a grounded electrode at the inner extremity of said threaded portion.

HECTOR RABEZZANA. 15
